[57] CLAIM

The ornamental design for a golf accessory organizer, as shown and described.

DESCRIPTION

FIG. 1 is a perspective view showing my new design;
FIG. 2 is a front view thereof;
FIG. 3 is a left end view thereof;
FIG. 4 is a right end view thereof;
FIG. 5 is a top view thereof;
FIG. 6 is a bottom view thereof;
FIG. 7 is a rear view thereof; and,
FIG. 8 is a perspective view thereof; the broken-line disclosure of various articles of golf equipment being for illustrative purposes only and forming no part of the claimed design.
